UNITED STATES PATENT OFFICE.

HARRY J. LYONS, OF TRENTON, NEW JERSEY, ASSIGNOR TO KEYSTONE POTTERY CO., OF TRENTON, NEW JERSEY, A CORPORATION OF NEW JERSEY.

DESIGN FOR A SUPPORTING LEG FOR LAVATORIES.

Application filed July 17, 1926. Serial No. 18,384. Term of patent 14 years.

To all whom it may concern:

Be it known that I, HARRY J. LYONS, a citizen of the United States, and a resident of Trenton, in the county of Mercer and State of New Jersey, have invented a new, original, and ornamental Design for Supporting Legs for Lavatories, of which the following is a specification, reference being had to the accompanying drawing, forming part thereof.

The figure is an elevational view of a supporting leg for lavatories, showing my new design.

I claim:

The ornamental design for a supporting leg for lavatories, as shown.

HARRY J. LYONS.
